UNITED STATES PATENT OFFICE.

ELMER GRAHAM, OF WRAY, COLORADO, ASSIGNOR TO THE GRAHAM COPY-HOLDER COMPANY, OF WRAY, COLORADO.

COPY-HOLDER.

1,313,812.

Specification of Letters Patent.

Patented Aug. 19, 1919.

Application filed March 30, 1918, Serial No. 225,712. Renewed June 24, 1919. Serial No. 306,489.

To all whom it may concern:

Be it known that I, ELMER GRAHAM, a citizen of the United States, and a resident of Wray, in the county of Yuma and State of Colorado, have invented a new and Improved Copy-Holder, of which the following is a full, clear, and exact description.

This invention relates to copy holders for use by typists or others making transcripts of records and has particular reference to a device of this character that is designed to hold in a convenient and reliable manner a more or less voluminous quantity or roll of the matter being copied.

15 Among the objects therefore of the invention is to provide a copy holder comprising a hollow cylindrical casing, having two parts hinged together longitudinally of the casing and having means to hold the parts closed 20 but with the sheet or sheets being copied projecting radially from within the casing along the joint or meeting line of the two casing parts, while the bulk of the matter is housed within the casing.

25 A further object of the invention is to provide certain improvements relating to the spacing means controlling the rotation of the casing according to predetermined angular amounts, such amounts being calculated 30 according to the width of the lines or other conditions.

Another object of the invention is to provide improved means for controlling the gripping of the paper and the releasing of 35 the paper with respect to the casing.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like 40 reference characters designate the same parts in the several views, and in which—

Figure 1 is a front elevation of the casing and parts immediately associated therewith.

Fig. 2 is an elevation of the left end of the 50 device with the lower portions in section on the line 2—2 of Fig. 5.

Fig. 3 is another elevation of the right end of the device.

Fig. 4 is a vertical transverse section on 55 the line 4—4 of Fig. 1.

Fig. 5 is a vertical section of the base on the line 5—5 of Fig. 2.

Fig. 6 is a sectional detail on the line 6—6 of Fig. 3;

Fig. 7 is an enlarged view indicating the 60 means to rotate or control the rotation of the casing, and

Figs. 8, 9, 10, and 11 are diagrams showing the different stages of the operation of the bail upon the sheet of paper during the 65 operation of the device.

Referring now more particularly to the drawings I show a base 10 of any suitable nature providing for the support of a standard 11 in upright position. This standard 70 is shown as comprising two plate members anchored to the base by screws or bolts. Between the upper ends of the plates is clamped an arm 12 by means of a clamping bolt 13 having a winged nut for hand operation. In the upper end of this arm 12 is clamped a crossbar 14 by means of a bolt 15 whereby the crossbar 14 may be adjusted angularly around its axis irrespective of the inclination of the upright arm 12 with respect to its clamping bolt 13. 75

The main part of the copy holder comprises a hollow cylindrical drum or casing 16, the end portions of which are journaled coaxially in a pair of brackets 17 and 18 85 extending forward parallel to each other from the ends of the crossbar 14. The pivot means comprises a short shaft 19 for each end of the casing having on its inner end a binding nut 20 and on its outer end a 90 finger piece 21 whereby the casing may be rotated conveniently and quickly by hand from either end. Said casing is divided longitudinally along a plane at one side of the axis of rotation thereof, the two parts 16^a 95 and 16^b thereof being hinged together around an axis 22 represented by a rod extending the full length of the casing through a pair of ears 23 formed on one of the parts and overlapping the perforated portions of 100 the other part. A spring 24 is arranged between the two parts of the casing in any suitable manner so as to tend to throw the cover portion 16^b open. As indicated this spring has its ends fixed to studs 24^a and 24^b 105 fixed to the parts 16^a and 16^b respectively. The force of this spring to throw the casing open is limited by means of a link 24^c pivoted to the stud 24^b and having a slot through which the stud 24^a projects. The 110

action of the spring, however, is normally resisted by a pair of catches 25 secured upon the ends of a rod 26 extending through the front portion of the casing just below the line of contact between the two free edges of the casing parts. These catches 25 co-operate with lugs 27 extending from the ends of the part 16^b, and since the catches are both mounted rigidly upon the same rod 26 they are both moved in unison. A spring 28 coiled within the casing around the rod 26 tends to hold the catches in locking position or engaged over the lugs 27. When the portion 16^b of the casing is swung to its closed position the lugs 27 ride over the cam portions 25' of the catches so as to deflect the catches against the force of the spring 28 for the purpose of allowing the lugs 27 to snap in behind the hook portions of the catches. When the lid portion of the casing is open the catches 25 are maintained in proper position to be engaged by the lugs 27, by means of a stop lug 29 carried by one or both of the ends of the main portion 16^a. The outer end of one catch 25 is provided with an outwardly projecting wing 30 whereby the operator by the use of his thumb or finger may release such catch from its lug 27 and by reason of the rigid shaft 26 the other catch will be released at the same time.

31 indicates a sheath of substantially semi-cylindrical form secured at its rear edge to the crossbar 14 and extending beneath the casing. The front edge portion of the sheath constitutes a line gage at 32 co-operating directly with the front portion of the casing or with the sheet of the copy rolled thereon. (See Fig. 4). Said front portion of the sheath is mounted upon a rod 33 which projects through pairs of ears 34 formed coincidentally with the formation of openings 35 in said sheath to accommodate a plurality of rollers 36 journaled upon the rod. The ends of the rod are supported in a pair of hangers 37 and 38 hung respectively upon a pair of studs 37' and 38' at the front ends of the brackets 17 and 18. The hanger 38 is projected upward above its pivot to form a finger piece or lever 39 which when pressed rearward lifts the rod 33 carrying its hangers 37 and 38 and the front portion of the sheath away from the casing releasing any hold thereof upon the paper.

As a further description of the operation of the rotating cylinder, serving as a casing or holder for a rolled book or roll of manuscript to be copied and whose two relatively movable parts serve as a gripping holder for the upper end of a sheet to be copied, mechanism externally of the roller co-operating with the sheet of paper as a line gage and guiding means, and also the bail including the bar 52 serving to throw the loose lower end of the sheet over out of

the range of the operator's vision, Fig. 8 indicates the relation of the parts above mentioned at the moment of the gripping of the upper end of the sheet S between the two parts of the cylinder, the paper 70 being thus held in gripped position by co-operation between the catches 25 and lugs 27. It will be understood that the parts just referred to co-operate in the manner illustrated upon a single loose sheet in 75 substantially the same manner as upon a sheet protruding through the casing from a roll or book within the casing. Fig. 9 is a view similar to Fig. 8 showing the cylinder after a complete rotation thereof, 80 all of the sheet except the lower end being wrapped around the cylinder and the bail shown in full lines as about to be released to throw the loose end of the sheet upward and rearward to the dot and dash line position shown at the left side thereof. It will be understood that during the rotation of the cylinder between the positions of Figs. 8 and 9 the bail bar 52, by riding or wiping over the rear portion of the stationary 85 mechanism will be brought down upon the outside of the cylinder and into the groove or pit 52' provided therefor at the front or free gripping edge of the upper portion 16^b and between the sheet and the 90 cylinder. After the sheet is gripped as indicated in Fig. 8 the operator by a simple movement gives a quick spin or rotation of the cylinder and at the end of this rotation, as indicated in Fig. 9, the loose or lower 100 end of the sheet is thrown over out of the way by the swinging of the bail around its axis 51 and by this time the first line of matter on the sheet will be brought into view just above the line gage 32. Fig. 10 105 indicates the result of the succeeding step by step actuation of the cylinder as a result of the transcribing operation. This figure shows the lower end of the sheet as still being located between the line gage or 110 gripping rollers and cylinder. At this connection it is to be noted that the operation of the device is not dependent upon any particular length of sheet. Fig. 11 is a view showing the action of the bail and upper 115 part 16^b of the cylinder when the extension 39 is pressed rearward far enough to open the cylinder, it being remembered that the first part of this actuation of the extension 39 serves to release the gripping rollers 120 and line gage while the latter part releases the catches 25. The preferred construction is such that the circumference of the cylinder approximately equals the length of the sheet, but if the sheet is 125 longer and is wrapped more than once around the cylinder it may be necessary to reverse the rotation of the cylinder slightly by the operation of the hand upon one of the knobs 21 to effect the release of the 130

sheet and opening of the cylinder as shown in Fig. 11. This apparatus is designed especially for copying or transcribing from ordinary folded court files or abstracts that can be manipulated in no other way as conveniently as within the hollow cylinder.

At either end of the device, preferably at the right, I provide a lever 40 pivoted upon the short shaft 19. This lever carries a pivotally mounted pawl 41, the point of which projects upward for coöperation with a fine toothed ratchet wheel 42 concentric with and fixed to the axis 19. A light spring 43 is connected to the pawl for the purpose of causing the point of the pawl to engage the teeth of the ratchet wheel when the lever 40 is lifted to actuate the casing. The pawl, however, is provided with a rearwardly projecting rounded end 44 coöperating with a V-ended stop 45 connected to a bracket 45' fixed to and extending downward from the bracket 17. These parts are so designed that when the lever 40 is returned by the spring to its idle position the rounded end or tail piece 44 of the pawl is received into the V of the stop 45 whereby the point of the pawl is withdrawn from the ratchet wheel against the force of the light spring 43 so the pawl is normally held free from the ratchet wheel and thus the operator by grasping either of the wheels or knobs 21 may rotate the casing rearward as well as forward at any time. When, however, the lever 40 is lifted to actuate the casing forward the pawl 41 will immediately engage a tooth of the ratchet wheel since the tail piece thereof will immediately leave the notch or V of the stop 45 during such movement of the lever 40. The stop 45 consequently constitutes a means to limit the downward movement of the lever 40.

The front end of the bracket 17 or any device connected thereto serves to support an adjustable cam shaped abutment 46 pivoted at 47 to the bracket. The bracket is provided with a series of notches or pits 48 into which a spring operated stud 49 is adapted to snap and temporarily hold the cam 46 in any desired position. The portion of the bracket having the holes or pits 48 is preferably graduated to represent various widths or distances between lines of matter to be copied. The finger piece 46' of the adjustable cam thus operates between relatively fixed ears 46^b but projects forward therefrom so that the manipulation of the cam may be easily effected by the operator by compression action, grasping said finger piece and the ear toward which it is to be moved between the thumb and finger so that the ear constitutes a fixed abutment or fulcrum to make the action positive and reliable.

At 50 I show a pair of levers connected to the ends of a rock shaft 51 on the out-

side of the ends of the cover section 16^b of the casing, the outer ends of these levers are connected by a steel ribbon 52 or the like. Said rock shaft 51 is controlled on the inside of the casing by a spring 53, the tendency of which is to throw the bail constituted by the two levers and steel ribbon rearward while the casing is being rotated. The rear or convex edges, however, of the levers 50 are adapted to ride upon rubber 75 rollers 14^a mounted upon the crossbar 14 whereby the steel ribbon 52 is swung inward against the surface of the casing while the casing rotates, the length of the levers being so designed that said ribbon will just bridge 80 over the joint between the free edges of the casing parts thereby relieving any depression or offset for the rollers 36 that otherwise would be incident to the edge of the casing which preferably is made somewhat 85 rounded to prevent any damage to the sheets of copy projecting therefrom.

In the practical operation of this copy holder any number of sheets such as a note book, loose leaves or part of a roll of matter to be copied are projected outward and downward over the line gage portion of the sheath, the bulk of the note book or other collection of sheets or leaves pertaining to the same copy being rolled up in any convenient manner and placed within the casing. The casing will now be closed either preliminary to or as a consequence of the rotation imparted thereto by one or the other of the finger pieces or knobs 21. While 90 the casing is thus being given a complete rotation the bail is rolled between the sheet and casing so that when the rotation is complete and the ribbon portion of the bail 95 passes the line gage the spring 53 pertaining thereto will snap the bail upward and rearward, causing the end of the sheet to be carried rearward therewith and held out of the line of vision and thereby the sheet to be copied beginning at its upper end is 100 110 presented in proper position for this purpose. In this condition the casing may be given a step by step rotation until the sheet is copied, then by touching the wing 30 the casing may be opened and another sheet will 115 be adjusted for treatment in the manner already described. In withdrawing the sheet from the machine, the line gage or sheath will be released therefrom by applying the thumb or finger to the extension 39. 120 Attention is now called to a wing 54 shown as constituting a rearward extension of the hanger 38 and having an arc shaped rear edge coöperating with a lug 55 formed on the adjacent hook 25. The curvature of 125 the wing edge is such that in normal position the lug 55 as it is carried with the hook around the axis of the casing passes along a path parallel to but spaced slightly from said edge. The finger piece 39 in addition 130

to serving to release the line gage from its gripping position on the paper also constitutes a means to open the casing. The operator to release the paper will grasp the 5 knob 21 and apply his thumb to the finger piece 39 whereupon an easy pressure on the finger piece will immediately throw the hanger 38 around its pivot 38' and so release the paper. This brings the curved edge 10 of the wing 54 into wiping engagement with the lug 55 so that the paper may be released without opening the casing if desired, or if the casing is to be opened a slightly further pressure on the finger piece 39 will cause 15 the wing acting through the lug 55 to release both of the hooks 25. Obviously the extent of swinging movement of the hanger 38 or wing 54 in the act of releasing the paper, but without releasing the hook, will 20 depend upon the normal clearance between the lug 55 and wing 54 or the length of the hooks that extend beyond the lugs 27. I thus provide a simple mechanical contrivance, one that is easily manipulated for 25 accomplishing two distinct objects or functions. The length of the arc of the wing 54 is such that the wing will engage the lug 55 for the purpose of unlocking and opening the casing at any point in a considerable 30 range relative to the joint in the casing beyond the line gage. It will be noted, therefore, that when the finger piece 39 is actuated to cause the unlocking and opening of the casing by reason of the coöperation between 35 the wing 54 and the lug 55, not only will the casing be opened so that the material therein may be removed, but also the same action of the finger piece in lifting the line gage away from the casing or sheet will 40 insure that the gripping rollers 36 will be withdrawn from gripping engagement with the sheet leaving it free as well as the mass within the casing to be removed or replaced as may be desired.

45 I claim:

1. The herein described copy holder comprising a hollow cylinder adapted to hold within it a roll of material to be copied and through the curved surface of which one or 50 more sheets are adapted to protrude outward, said cylinder comprising two relatively movable parts for the insertion of said roll and constituting gripping means for the protruding sheet or sheets, means to 55 support the cylinder for rotation, means to impart to it a step-by-step rotation, and a line gage coöperating with the projecting sheet or sheets.

2. In a copy holder of the class set forth, 60 a hollow cylindrical casing comprising two parts hinged together and adapted to house within the same a roll or quantity of matter to be copied and providing for the protruding therefrom and gripping of a sheet of 65 such matter along the meeting line of the

free edge portions of said casing parts, means tending to separate the casing parts, means resisting said tendency, and means to rotate the casing.

3. In a copy holder of the character set forth, the combination of relatively stationary supports including a sheath, the edge of which constitutes a line gage, a hollow device journaled for rotation in said support adjacent to said line gage, means to secure a sheet to be copied to said device providing for the sheet to roll upon the outer surface thereof when the device is rotated, and means carried by said device tending to automatically lift the free end of the sheet 80 and throw it rearward away from the line of vision after it passes said line gage.

4. In a copy holder of the character set forth, the combination of a relatively stationary support including a line gage, a rotary device journaled in said support and coöperating with said line gage, means to attach the upper edge of a sheet to be copied to said rotary device whereby when the device is rotated said sheet will be wrapped 90 around the device between the same and the line gage, means to rotate the device, and means to throw the free end of the sheet away from the line gage and line of vision, substantially as set forth.

5. In a copy holder, the combination of a relatively stationary support one edge of which constitutes a line gage, a hollow cylindrical casing journaled in said support and with the front of which casing the line 100 gage coöperates, said casing comprising two portions hinged together, means tending to open the casing, means holding the casing closed but releasable from either end thereof, means to rotate the casing, and a spring 105 operated bail pivoted upon the casing serving to throw the free end of the sheet away from the line gage.

6. In a copy holder, a casing comprising two portions hinged together, means tending 110 to open the casing, means holding the casing closed but releasable from either end thereof, supporting means for the casing, means to rotate the casing in its supporting means, and a spring operated bail pivoted upon the 115 casing and rotatable therewith and serving to throw the free end of the sheet out of the line of vision of the operator.

7. The herein described copy holder comprising a rotary member, a support for said member, an actuating wheel coaxial of and fixed to said rotary member, an actuating lever adjacent to said wheel, an engaging member pivotally mounted upon the lever, a spring acting upon the engaging member to 120 cause it to engage said wheel when the lever is actuated to rotate the rotary member and also serving to return the lever to idle position after such actuation, and a stop member acting automatically upon the engaging 125 130

member in idle position to hold it free from said wheel.

8. In a copy holder, the combination of a support, a rotary holding member journaled 5 in said support, a ratchet wheel fixed to the rotary member and coaxial therewith, an oscillating lever in the form of a bell crank adjacent to the wheel, a pawl pivoted upon the lever and engageable with the teeth of 10 the wheel when the lever is actuated to rotate the rotary member, and a fixed stop having a beveled edge against which the end of said pawl remote from its point engages when the lever returns to normal or idle position, said 15 stop acting to swing the pawl on its pivot to

cause the point of the pawl to be withdrawn from the teeth of the wheel allowing the wheel to be rotated freely in either direction.

9. In a device of the character set forth, the combination of a relatively fixed support, 20 a hollow copy holding casing journaled for rotation therein, said casing comprising relatively fixed and movable parts, means to lock the parts together, a member coöperating with the casing serving as a line gage for a 25 sheet projecting from the inside of the casing, and a single hand operated member serving by single movement to release the line gage and unlock said locking means.

ELMER GRAHAM.
